LID FOR A BASKET PURSE OR THE LIKE

Patricia A. Simmons, 16125 Mack Ave.,
Grosse Pointe, Mich. 48224

Filed June 21, 1971, Ser. No. 155,396

Term of patent 14 years

Int. Cl. D3—01

U.S. Cl. D87—3 F

FIG. 1

FIG. 2

FIG. 1 is a perspective view of a lid for a basket purse or the like, showing my new design;
FIG. 2 is a perspective view of the opposite side; and
FIG. 3 is a sectional view on line 3—3 of FIG. 1.
I claim:

The ornamental design for a lid for a basket purse or the like, as shown and described.
